US00D640973S

(12) **United States Design Patent**
Katsaros

(10) **Patent No.:** **US D640,973 S**
(45) **Date of Patent:** **** Jul. 5, 2011**

(54) **SOLAR POWERED BATTERY CHARGER**

(76) Inventor: **Stephen Katsaros**, Denver, CO (US)

(**) Term: **14 Years**

(21) Appl. No.: **29/385,987**

(22) Filed: **Feb. 23, 2011**

(51) LOC (9) Cl. **13-02**

(52) U.S. Cl. **D13/102; D13/107**

(58) **Field of Classification Search** D13/101, D13/102, 107-110, 118-119, 184; D14/251, D14/253, 432, 434; 320/101, 102, 107-115, 320/120; 136/206, 243-245

See application file for complete search history.

(57) **CLAIM**

The ornamental design for a solar powered battery charger, as shown and described.

DESCRIPTION

FIG. 1 is an isometric view of a solar powered battery charger showing my new design;

FIG. 2 is a right elevation view thereof;

FIG. 3 is a left elevation view thereof;

FIG. 4 is a top plan view thereof;

FIG. 5 is a bottom plan view thereof; and,

FIG. 6 is a rear elevation view thereof.
